Patented Sept. 21, 1926.

UNITED STATES PATENT OFFICE.

WILLIAM THOMAS BARKER, OF WATERBURY, CONNECTICUT.

CLEANING DEVICE FOR ROTATING BRUSHES.

Application filed October 12, 1922. Serial No. 594,220.

My invention relates to cleaning devices for rotating brushes, especially to such devices for efficiently cleaning brushes that are substantially cylindrical in form, as revolving brushes in vacuum cleaners or carpet sweepers of various types.

The cleaning of brushes of the above-mentioned class has always presented a more or less difficult problem, since they are mounted so as to rather avoid cleaning them efficiently because of the small area of surface exposed at one time. And yet, these brushes need cleaning often, as they fill up by the nature of their use, with all kinds of dust, filaments, threads, hair and tufts of various materials. It is the purpose of this device to make possible the cleaning of the brushes without dismounting, and by manually operated means.

A valuable object of this invention is to clean such brushes while the latter are being rotated and by holding the new device in proximity to the surface of the brush. It is also a further object to clean the brush by contact with a maximum of the peripheral surface of the brush.

The details of the application of my improvement to the function sought will be explained as the structural description proceeds.

The above-stated and other objects of my invention are attained by structure illustrated in the accompanying drawings in which,

Figure 1 is a perspective view of my cleaning device, as seen from the inner surface thereof, and

Figure 2 is a transverse section of the body of the device, and as applied to a rotating brush shown in dotted lines.

In the drawings in which similar reference characters are employed to indicate corresponding parts throughout the several views, the letter A designates a sheet of card clothing or other foundation for mounting large numbers of steel teeth B thereon, by which means the latter are secured within the said sheet may be secured within a metallic frame C whose side edges F are bent over toward the said teeth to secure the latter in position on the backing. It is a purpose of this device to make possible the easy cleaning of a brush having a convex surface, such as the peripheral surface of a rotating brush X which is illustrated in Fig. 2 in dotted lines only. This curved

surface can be most readily cleaned by a concave cleaning surface, and the surface of my device is therefore concave as shown at K in said view.

To so mount the said teeth, the inner surface of the metal frame C is made concave and the sheet A fitted to said surface. To mount the cleaning agent B for manipulation the device is applied to a heavy wire handle D formed by doubling the ends of a wire strip together and applying the spaced ends to the surface of the sheet near the edges thereof, just outside the teeth, and then bending the metal edges F over the wire at E and thereby exerting pressure on the sheet surface. The form of the extended handle part may be fashioned as may be desired for conveniently grasping by the hand.

The cleaning device is not only curved transversely but also longitudinally as shown in Fig. 1, the latter feature making possible the application of the concave form of the teeth or otherwise roughened surface to a rotating brush surface without exposing the handle and the hand grasping the same to the brush being cleaned. To further secure the toothed or otherwise roughened element upon the metal frame, the ends of the latter are also bent inward as at G and H and clamped down upon the sheet A.

It is to be noted that I have thus devised a cleaning device which is itself a form of brush, and is formed in a concave fashion on the brush side in cross section but convex in a longitudinal section, as shown clearly in Fig. 1. This convexity is for the purpose mentioned in the preceding paragraph.

The materials mentioned in the above description need not be used just as stated, as my invention does not consist in the selection of material, though they have been found very satisfactory for the purpose, but many changes may be made in the nature of substances used to attain a particular object, without abandoning the spirit of my invention as here shown and described and later recited in the claims. For example, while reference is herein made to card clothing as the means for cleaning a brush, it is by no means essential that metal teeth shall be used or that card clothing be the form of such metal teeth for the instrument employed. In some cases, it may be desired to

use some other form of cleaning surface, or that other material be used for the surface employed.

While the inner surface of my cleaning device is shown as concave transversely and convex longitudinally, in some situations it may be desirable to use a cleaner device concave in the transverse plane only, and I especially note that such construction is within the terms of this disclosure as outlined and recited in the claims.

It is also to be noted that I am by no means restricted to the particular form of handle shown and described. Any handle element may be used that can be applied upon the edges of the sheet and pressed thereon by the bent over strips F of the frame.

The form of metal used for the frame C may well be aluminum or some of its alloys, but in some cases other metal may be substituted therefor.

Having described my invention, what I desire to secure by Letters Patent and what I claim is,—

1. A brush cleaning device comprising an elongated, curved, supporting sheet, metal teeth mounted on the concave surface of the sheet, a rigid, metallic frame member secured to the side edges of said sheet adjacent its tooth surface and extending longitudinally thereof, and a wire handle extending from one end of the device with the wire ends secured to the side edges of said member.

2. A cleaning device for rotating brushes comprising an elongated sheet, metallic teeth mounted upon said sheet, rigid means for mounting said sheet to form a toothed, con-

cave surface in cross section of the sheet for convenient application of the said toothed surface to the convex surface of brushes to clean the latter, and a supporting handle secured to one end of the device and extending longitudinally thereof.

3. An elongated brush cleaning device comprising a support having a toothed surface concave in cross section for contact with a convex surface of a rotating brush, and convex in longitudinal section to avoid contact of the operator's hand with the brush, and a supporting handle extending longitudinally from said support.

4. A cleaning device for rotating brushes comprising a sheet, metallic teeth mounted on said sheet, a metallic backing for mounting said sheet to provide a toothed surface concave in cross section and convex in longitudinal section, a bent rod serving as a supporting handle for the device, the spaced rod ends being secured to the edges of said sheet, and the edges of said backing being bent up over the rod ends and clamped down on the sheet edges.

5. A brush cleaning device comprising a support having a surface provided with metallic teeth, said surface being concave in cross section and convex in a longitudinal section, whereby the device will contact the surface of a curved brush to be cleaned over an appreciable arc, and yet permit one end of the device to be grasped by the operator's hand without contacting the surface of said brush.

In testimony whereof I hereunto affix my signature.

WILLIAM THOMAS BARKER,
